CLAIM

The ornamental design for a bolster dressing, as shown and described.

DESCRIPTION

FIG. 1 is a perspective view of the present invention of a bolster dressing;

FIG. 2 is a top view of the bolster dressing of FIG. 1;

FIG. 3 is a side view of the bolster dressing of FIG. 1, with the opposite side view being a mirror image thereof;

FIG. 4 is an end view of the bolster dressing of FIG. 1;

FIG. 5 is a bottom view of the bolster dressing of FIG. 1; and,

FIG. 6 is an opposite end view of the bolster dressing of FIG. 4.
